CLAIM

The ornamental design for a paint bucket with cover, as shown and described.

DESCRIPTION

FIG. 1 is a front perspective view on an enlarged scale of a paint bucket with cover, with cover separated from paint bucket, showing my new design;

FIG. 2 is a front elevational view thereof, with cover on the paint bucket;

FIG. 3 is a rear elevational view thereof;

FIG. 4 is a right side elevational view thereof;

FIG. 5 is a left side elevational view thereof;

FIG. 6 is a bottom plan view thereof; and,

FIG. 7 is a top plan view thereof.
